M. B. BEHRMAN

CHECK PROTECTOR

Filed April 20, 1923

Inventor:

MARCUS B. BEHRMAN.

By his Attorney,

Charles L. Gill.

UNITED STATES PATENT OFFICE.

MARCUS B. BEHRMAN, OF BROOKLYN, NEW YORK.

CHECK PROTECTOR.

Application filed April 20, 1923. Serial No. 633,402.

To all whom it may concern:

Be it known that I, MARCUS B. BEHRMAN, a citizen of the United States, and a resident of Brooklyn, in the county of Kings and State of New York, have invented certain new and useful Improvements in Check Protectors, of which the following is a specification.

The invention relates to means for preventing bank-checks and the like from being successfully altered by erasure or otherwise, and more especially to a small compact check protector adapted to be carried in a vest or other pocket and which is preferably incorporated in a fountain-pen structure so as to be handy for use by a person employing a pocket check-book.

In its preferred form the check protector of my invention is carried on the closed end 20 of a fountain-pen cap and comprises a toothed roller and a roller ink pad therefor, and when the protector is not in use it is concealed by a supplemental cap which harmonizes with the general appearance of the 25 fountain pen structure. The pen structure serves as a handle for the check-protector when the latter is in use, or the pen-cap alone may serve as such handle. The toothed roller has a series of annular rows of teeth 30 adapted when the roller is rolled under pressure against a check to puncture the same and thus prevent alteration in the figures or writings on the check, and said roller while being rolled against the check also rolls 35 against the ink-pad and becomes inked on the ends of its teeth, with the result that while the roller is puncturing the check it leaves an ink impression on the check at the punctures therein, said ink impression being 40 approximately in the form of dots corresponding with the teeth on the roller or the punctures made thereby and cooperating with the punctures in preventing successful alteration of the check.

The invention will be fully understood from the detailed description hereinafter presented, reference being had to the accompanying drawings, in which:

Fig. 1 is a side view of a fountain pen 50 embodying my invention, the pen being shown in normal closed condition;

Fig. 2 is a side view, partly broken away and partly in section, of the same, the supplemental cap for concealing the check-protector

features being shown in vertical section and as having been lifted above the same;

Fig. 3 is a vertical section, on an enlarged scale, through the enclosing cap for the pen-point and through the check-protecting features of my invention applied on the outer end of said cap;

Fig. 4 is a vertical transverse section through a portion of the same taken on the dotted line 4—4 of Fig. 3, the supplemental cap for the check-protector features being omitted;

Fig. 5 is a plan view looking down on Fig. 4;

Fig. 6 is a horizontal section taken on the dotted line 6—6 of Fig. 3, and

Fig. 7 is a detached vertical section of the frame used for carrying the puncturing-roller and positioning the pad-roller and which frame is detachably applied upon the outer end of the main cap for enclosing the pen-point when the pen is not in use for writing purposes.

In the drawings, 10 designates a fountain-pen having a cap 11 to be applied over the pen point when necessary, said fountain-pen and said cap being employed in the usual manner and, except for the presence of my invention connected with the outer end of the cap, being of any usual or suitable construction. My invention is applied to the closed end of the cap 11 and in no manner modifies the construction of any other member of the pen.

The outer end of the cap 11 constitutes a base 12 for the features of the check protector, and formed on the base 12 is an upwardly extending cylindrical sleeve 13 which is less in diameter than the cap 11 and is externally screw-threaded, an annular shoulder 14 being formed on the base 12 at the lower edge of and surrounding the threaded portion of the sleeve 13. Within the sleeve 13 is a cup-like chamber 15.

The other features of the check protector comprise the rotary puncturing roller 16, the rotary ink-pad roller 17, the cylindrical frame 18 carrying said roller 16 and positioning the roller 17, and the removable supplemental cap 19 adapted to fit over and conceal the check protector features, as shown in Figs. 1 and 3.

The frame 18 is cylindrical and open at

both ends and is internally threaded, as at 20, to screw downwardly upon the externally threaded sleeve 13 and against the shoulder 14. The frame 18 at its extreme lower end 5 has an external thread 21 (Fig. 7) to be engaged by an internal thread 22 (Fig. 2) on the inner surface of the lower end of the cap 19, whereby said cap may be secured in place covering the check protector features, 10 as shown in Fig. 3, wherein it may be seen that the cap engages the shoulder 14 and that the outer side surface of the cap 19 is on the same plane as the side surface of the cap 11 and appears as a continuation there- 15 of, as shown in Fig. 1.

The threaded lower end of the frame 18 is formed in two opposite sides with interior vertical grooves 23, and said frame at its upper portion is, at opposite sides, inclined 20 downwardly on diverging lines to form standards 24, which have vertically elongated openings 25 to serve as bearings for the ends of the axle or shaft 26 of the puncturing roller 16, the elongation of said openings 25 being, for one purpose, to permit the roller 16 to yieldingly engage the roller-pad 17 when the roller 16 is pushed along over the surface of a check or the like.

The roller 16 is of steel and formed with 30 a series of annular side by side rows of sharp-pointed teeth, and said roller is of suitable width to puncture, when rolled firmly over the same, the portions of a check or the like on which the amount or face 35 value has been written or printed. The roller 16 and roller 17 are so relatively positioned that when the roller 16 is rolled against the surface of a check it will also roll against the pad-roller 17 and being 40 inked thereby, will transfer the ink to the punctures in the check made by the teeth of the roller 16, there thus being a double safeguard in the use of the invention, one being the puncturing of the check by means of the 45 roller 16 and the second being the inking of the check at the punctures made by said roller 16.

In assembling the parts of the check protector the toothed roller 16 is applied to the 50 frame 18 and the ends of the axle of the pad roller 17 are, on the inversion of the frame 18, dropped into the grooves 23 of said frame, and thereupon the frame 18 is screwed upon the threaded sleeve 13 and 55 against the shoulder 14, and one result of this action is to position the ends of the axle of the pad-roller 17 freely upon the upper edge of the sleeve 13, while at the same time said ends of said axle are held against lateral motion by the opposite walls of the 60 grooves 23. The elongated slots 25 in the standards 24 permit me to secure a light engagement of the roller 16 with the roller 17 during the non-use of the protector. When

the protector is in use the pressure against 65 the roller 16 will cause said roller to move more firmly against the pad-roller 17 and receive its supply of ink therefrom, the elongated slots 25 permitting the roller 16 to move firmly against the roller 17 when said 70 roller 16 is under pressure, as in use.

After the parts of the protector have been assembled, the cap 19 may be applied over them so as to conceal and protect said parts and also afford a finish to the fountain-pen. 75 When the protector is to be used, the cap 19 is removed and thereupon the protector is ready for use, the cap 11 or the fountain pen as a whole serving as a handle therefor.

The check-protector may be a separate 80 article of sale from the fountain-pen, since, as shown in Fig. 3, the pen proper is not a necessary part of the protector. I prefer however that the cap 11 be such that it may serve for fountain-pen purposes.

My invention provides a highly efficient 85 and very compact check protector which may be conveniently carried on a pen or separately in one's pocket for use at any time a 90 check may be drawn.

I have shown and described the most desirable form of my invention at present known to me, but I do not wish to be limited to all of the details of form and construction described, since I am aware that these 95 details may be modified without departure from my invention and within the scope of the appended claims.

What I claim as my invention and desire 100 to secure by Letters-Patent, is:

1. A check protector comprising a handle affording on one end a base member having an annular threaded sleeve extending above the same, a cylindrical frame having a threaded lower portion engaging the thread on said sleeve and affording outwardly extending side standards, an ink pad roller positioned within the inner portion of said frame, a puncturing roller journalled in said standards over and in parallelism with said pad roller and adapted to engage the same and a removable cap fitting over said frame and rollers, said puncturing roller having a series of rows of sharp pointed teeth over its surface, and said frame having grooves in its inner opposite vertical walls receiving the ends of the shaft of said pad roller, for positioning said roller, said grooves being open at their lower ends to receive said shaft and confining the same at 110 the sides and outer extremities of the end portions thereof.

2. A check protector comprising a fountain-pen pen-protecting cap having at its closed end a base member on which is an annular threaded sleeve extending above the same, a cylindrical frame having a threaded lower portion engaging the thread on said

sleeve and affording outwardly extending side standards, an ink-pad roller positioned within the inner portion of said frame, a puncturing roller journaled in said standards over and in parallelism with said pad-⁵ roller and adapted to engage the same, and a removable cap fitting over said frame and

rollers and harmonizing with said pen-protecting cap in diameter and general appearance.

Signed at New York city, in the county of New York and State of New York, this 2nd day of April, A. D. 1923.

MARCUS B. BEHRMAN.
